UNITED STATES PATENT OFFICE

165,673

CALENDAR WRISTBAND

Howard Steven Strouth, Forest Hills, N. Y.

Application August 31, 1950, Serial No. 11,997

Term of patent 3½ years

(Cl. D45—4)

To all whom it may concern:

Be it known that I, Howard Steven Strouth, a citizen of the United States of America, residing in Forest Hills L. I., county of Queens, State of New York, have invented a new, original, and ornamental Design for a Calendar Wristband, of which the following is a specification, reference being had to the accompanying drawing, forming part thereof.

Fig. 1 is a top plan view of a calendar wristband showing my new design.

Figs. 2 and 3 are enlarged top plan and side elevational views, respectively, of one of the calendar connecting links.

The dominant features of my design resides in the portions shown in solid lines.

I claim:

The ornamental design for a calendar wristband, as shown and described.

HOWARD STEVEN STROUTH.
